REED GAUGE FOR MUSICAL INSTRUMENTS

Filed Aug. 14, 1951

UNITED STATES PATENT OFFICE

2,672,782

REED GAUGE FOR MUSICAL INSTRUMENTS

Jacob Topor, Wheeling, W. Va.

Application August 14, 1951, Serial No. 241,760

2 Claims. (Cl. 84—364)

1

The present invention relates to a reed gauge setter for use with saxophones, clarinets and the like.

At the present time musicians experience a great deal of difficulty in positioning a reed in the exact position on a mouthpiece of wind instruments. It is very important to a musician that the reed be in proper position, otherwise the fine tones of the instrument will not be achieved.

It is an object of the present invention to provide a device that will positively position a reed on a mouthpiece in the desired position for maximum efficiency.

Another object of the present invention is the provision of means on the device for centering a reed on a mouthpiece.

A still further object of the present invention is the provision of means for locking the reed in position.

A still further object of the present invention is the provision of means in the device for seating one end of a reed.

A still further object of the present invention is the provision of means for locking the device to a mouthpiece.

Other and further objects of the present invention will appear from the following description, when taken in connection with the accompanying drawing, in which:

Figure 1 is a perspective view of a conventional mouthpiece equipped with a preferred embodiment of the invention.

Figure 2 is a sectional view taken on line 2—2 of Figure 1.

Figure 3 is a fragmentary top plan view illustrating the adjustable lugs, a portion being broken away to show the groove that receives one end of a reed.

Figure 4 is a perspective view of a modified form of the invention.

Figure 5 is a sectional view taken on line 5—5 of Figure 4.

Figure 6 is a fragmentary top plan view of the modified form of the invention shown in Figure 4, and

Figure 7 is a fragmentary sectional view of the modified form of the invention and showing the reed engaging means.

Referring to the drawing in detail which illustrates the preferred embodiment of the present invention and in which like numerals indicate similar parts throughout the various views.

The numeral 10 represents a conventional mouthpiece of a saxophone, clarinet or the like, having a conventional clamp 11 for holding a reed 12 on the flat face 13 of the mouthpiece.

2

Encompassing the body of the mouthpiece 10 is a band 14 of suitable material, having a ridge 15, and smaller ridges 16, the inner ends of which are in spaced relation to each other forming an opening 17. The bottom faces 18 of the smaller ridges 16 are in spaced relation to the top face of ridge 15 forming slots 19. The top face of ridge 15 is provided with a recess 20 for receiving one end 21 of reed 12.

10 There is provided lugs 22 each having legs 23 and 24, the legs 24 engaging the slots 19 and being provided with a slotted portion 25 that permits transverse adjustment of the lugs. The inner face of the legs 23 are adapted to engage 15 the side edges of the reed 12 to impinge the reed in its exact position on the mouthpiece. The lugs 22 are held for slidable engagement in the slots 19 by screws 26 that engage apertures in the ridge 15 and a threaded bore in the ridges 16 to secure the 20 lugs in a fixed position.

The band 14 is secured on the mouthpiece 10 by a screw 27 that engages the lugs 28 that are an integral part of the band.

In the modified form of the invention as shown 25 in Figures 4 to 7 there is provided a band 30 for positioning on a mouthpiece a reed 31 having semi-circular portions 32 and 33 and a groove in the heel end.

The band 30 is provided with a ridge 35 having a reduced extension 36 that projects beyond one peripheral edge, one edge of the reduced extension being of arcuate configuration. The edge 37 of band 30 serves as a seat or abutment for the heel of the reed 31. The band 30 is secured on a mouthpiece 10 by screws 38 that engage lugs 39.

In use of the device shown in Figure 1, the band 14 is placed upon the mouthpiece 10, with the opening 17 in alignment with the heel end of the flat surface 13, the screw 27 then tightened. The ligature 11 being loose on the mouthpiece, permits the reed 12 to be pushed into the opening 17 until the end 21 is seated in the recess or groove 20. The lugs 22 are then adjusted, the legs 23 being in engagement with the side edges of the reed 12. The legs 24 being slidable in the grooves 19, the reed may be moved to the left or right until it is in the desired position, and at this point the screws 26 are tightened and secure the lugs in fixed position. The screws on the ligature clamp 11 are then tightened which secures the ligature in place as well as holding the reed in place. From the above it can be seen that the reed will be properly positioned and held on the mouthpiece for maximum performance and it cannot be casually moved out of fixed position.

In use of the modified form of the invention

shown in Figure 4, the band 30 is placed upon the mouthpiece 10, the extension or projection 36 being midway the side edges of the flat face 13, the screw 38 is then tightened which locks the band on the mouthpiece. The reed 31 is then positioned on the flat surface of the mouthpiece and pushed under the ligature and toward the band until the groove or slot 34 engages the projection or extension 36, holding the reed in position, at this point the ligature screws are tightened which locks the ligature on the mouthpiece as well as the reed.

I wish to have it understood that changes may be made and details of construction varied without departing from the principles of this invention, and I therefore do not wish to limit myself to the exact showing, and that changes may be made without departing from the spirit of the invention or the claims hereto appended.

I claim:

1. A reed setter for the conventional mouthpiece of musical instruments comprising an adjustable band having a recess therein, adjustable L-shaped lugs on either side of said recess each

of said lugs being angularly adjustable to accurately position the heel end of said reed in said recess.

2. A reed positioning device for the mouthpiece of musical instruments, said device comprising an adjustable band having a recess therein for carrying means to engage the heel end of a reed held by a conventional ligature, said means comprising individually adjustable L-shaped members.

JACOB TOPOR.
